UNITED STATES PATENT OFFICE.

ANDREW G. BUCHMAN, OF KENOSHA, WISCONSIN.

DETACHABLE RUBBER HEEL.

1,366,518.

specification of Letters Patent. Patented Jan. 25, 1921.

Application filed August 19, 1919. Serial No. 318,479.

To all whom it may concern:

Be it known that I, ANDREW G. BUCHMAN, a citizen of the United States, residing at Kenosha, in the county of Kenosha and 5 State of Wisconsin, have invented certain new and useful Improvements in Detachable Rubber Heels, of which the following is a specification.

This invention relates in general to shoes 10 and more particularly to the heels thereof, having for its principal object the production of a detachable heel.

Another object of this invention is the 15 production of a detachable heel preferably of the rubber type, although of course, it may be of leather, whereby when it is necessary to repair the heel of a shoe it may be done by a layman at only the nominal cost of the heel.

20 Another object of this invention is the production of a detachable rubber heel having a plurality of cups therein having efficient means for holding the same in position while heads are carried upon the permanent 25 heel portion of the shoe for being received within the cup to detachably hold the heel in position, thus providing a super-resilient, durable and economical heel.

One practical form of construction and 30 assembly of the present invention will be hereinafter described, and as illustrated in the drawing, in which

Figure 1 is a sectional view through the detachable heel and shoe.

35 Fig. 2 is a bottom plan view of the fixed heel of the shoe.

Fig. 3 is a top plan view of the detachable rubber heel with the cups in position.

40 Fig. 4 is a longitudinal section through the detachable heel *per se* taken on the line 4—4 of Fig. 3.

Fig. 5 is a transverse section of the detachable heel taken on the line 5—5 of Fig. 3.

45 Fig. 6 is an enlarged fragmentary detail sectional view through a portion of the detachable shoe heel when secured upon the fixed heel of the shoe showing specifically the construction of the cup and the head and their manner of engagement.

50 In a preferred embodiment of the present invention, about to be specifically described, for the purpose of illustration, a portion of a shoe is illustrated at 10 having the usual sole 11 and fixed heel 12. Any suitable form 55 of shoe or any size may be employed in con-

nexion with the present invention as the specific shape does not enter into the novelty, since the feature of the invention resides in the specific means by which the heel is detachably supported.

60 The detachable rubber heel is shown at 13 and is of substantially conventional shape and form as illustrated in Figs. 3, 4 and 5. The heel is provided with a dished upper surface 14 so that when the heel is fixed upon the fixed heel the forward end thereof will bind tightly in engagement with the fixed heel to form a tight closure and thus 65 preventing entrance of moisture between the fixed and detachable heel and also acting as 70 a tensioning device for holding the connections between the detachable heel and the fixed heel from becoming loose under any circumstances.

75 When the rubber heel 14 is being formed, a plurality of cups are molded therein, the construction of the cups being clearly shown in Figs. 3, 4 and 6. Each cup comprises a base 15 of considerable size and a wall 16 rises from one surface of the base 15 remote 80 from the periphery of the base. Accordingly, when the heel is being formed and the cup is molded therein a part of the rubber will overlie the upper surface of the base as 85 shown clearly in Fig. 6 to permanently fix the cup within the heel. The wall 16 is provided with an annular bead 17 at its upper edge, the bead being provided with a concaved inner surface for receiving a locking 90 ring 18. The heel 13 is provided with a 95 socket 19 extending thereinto from its upper surface, thus allowing free access to the cups carried thereby as illustrated in Fig. 3. It will be noted however, that the portion of the rubber heel 13 below the base of each cup is even and solid, thus increasing the resiliency of the rubber heel as well as its time of usefulness and also prevents any marring of the floor over which the shoe may pass while it will further be noted that 100 no portions are provided in which mud or refuse may collect at times and be discharged on polished surfaces or elsewhere.

105 A plurality of heads are fixed upon the fixed heel as shown in Fig. 2 and each head has a central depression 21 whereby a nail or other securing element 22 may be passed therethrough and embedded in the fixed heel 12 thus permanently securing the head upon the fixed heel. It will be noted that the body 110

of the head 20 has a concaved outer surface as shown at 23, thus providing a bearing portion upon which the locking ring 18 may engage as shown in Fig. 6. The head 20 is 5 flanged as shown at 24 whereby the head may evenly and firmly bear upon the lower surface of the fixed heel 12.

As many heads may be fixed upon the fixed heel 12 and as many cups may be 10 formed in the detachable heel 13 as may be desired. It being preferable of course to include the same points where the greatest strain takes place. All that is necessary to attach the heel 14 is to place the same 15 below the fixed heel 12 so that the heads will be in registry with the cups. Pressure then being applied to the shoe will cause the heads to pass into the cups at which time the locking rings 18 and walls 16 may yield slightly 20 until the enlarged lower ends of the heads are passed below the rings 18 and then the cups will again assume their normal positions so that the locking rings will lock the cups in engagement with the heads and thus 25 firmly fix the detachable heel upon the fixed heel.

If it is desired to replace the detachable heel for instance after the same has been worn out or in the event there is a tendency 30 of the user to "run over" his heels upon one side or the other, then an implement may be inserted between the detachable heel and the fixed heel and the detachable heel may be pried off, causing the cups to disengage 35 the heads. At this time new heels may be placed upon the fixed heel or the rubber heels in the event they have been "run over", are reversed, that is placed on opposite heels so that they may be worn for a 40 considerable period longer.

It will be seen that the device may be very simply constructed, thus minimizing the cost of production, while the very simplicity also increases the efficiency and 45 operation. The cost of production of the sheet metal structures will be very small and as the cups are molded in the rubber heels all the person using the same has to do is to secure the heads upon the fixed heel of the 50 shoe and then by placing the rubber heels below the fixed heels of the shoe and pressing upon the rubber heels properly will hold the rubber heels in position very easily. Accordingly, a layman may accomplish this 55 result without any difficulty thus minimizing the cost of repairing his heels to a very nominal expense.

As above pointed out, owing to the fact that the rubber heels are preferably dished 60 when the heads engage the cups the outer portions of the rubber heels will be more firmly held upon the lower surfaces of the fixed heel, thus providing a tight closure for preventing the entrance of moisture or

any refuse between the two heels, while the 65 lower surface of the detachable heel will increase the resiliency of the same and will also prevent the same from marking polished surfaces as is so often the case with the ordinary rubber heels now in use and 70 also the heels are often secured so as to bring about injury to said surfaces.

It will be therefore seen that a very simple and efficient detachable rubber heel has been provided wherein the cups are so arranged that when the heels are being molded or formed the cups will be pressed therein so as to be permanently retained after the rubber heel has been produced. This is accomplished by the manner in which 80 the portions of the base of each cup projects beyond the outer surfaces of the wall thereof. The wall and locking ring present a yielding or resilient locking engagement 85 for engagement with the heads which are permanently mounted upon the fixed heel of the shoe. It will further be understood that although the heel 13 is designated as a rubber heel without departing from the 90 spirit of the invention it might be a composite leather heel wherein the cups are embedded as the sections of the lever are connected together so that the layman could just as well repair his first heels with leather heels, just as above stated, the novelty in the case includes more specifically 95 the manner of connecting the detachable heel to the fixed heel than to any other feature of construction.

Although the invention as described has 100 been indicated as a half heel it is obvious without departing from the spirit of the invention, the heads may be permanently fixed upon the sole of the shoe at the heel thereof to connect a full heel in position just as 105 readily as a half heel the construction and operation of the device being under all conditions the same.

The foregoing description and the drawings have reference to what may be considered the preferred or approved form of my invention. It is to be understood that I may make such changes in construction and arrangement and combination of parts, materials, dimensions, etcetera, as may prove expedient and fall within the scope of the appended claim.

Having thus fully described my invention what I claim as new and desire to secure by Letters Patent is:—

In combination with a shoe including a fixed heel, heads affixed upon said fixed heel, a detachable heel having sockets therein, cups positioned within said sockets, each cup comprising a base having a wall extending from one surface remote from the periphery thereof, the wall having a bead adjacent its upper edge, the bead being pro-

vided with a concaved inner surface, for holding the cup against displacement, a locking ring carried by said bead, whereby the heads on said fixed heel may be passed 5 into the cups to be engaged by the locking means, thus releasably connecting the detachable heel to the fixed heel.

In testimony whereof I affix my signature in presence of two witnesses.

ANDREW G. BUCHMAN.
